Martha May Hagedorn, Gresham, Oreg.

Application April 26, 1944, Serial No. 113,379

Term of patent 14 years

(Cl. D33—19)

To all whom it may concern:

Be it known that I, Martha May Hagedorn, a citizen of the United States, residing at Gresham, in the county of Multnomah and State of Oregon, have invented a new, original, and ornamental Design for a Towel Cabinet or Similar Article, of which the following is a specification, reference being had to the accompanying drawings, forming part thereof.

Figure 1 is a front elevational view of a towel cabinet or similar article, showing my new design, the doors being illustrated in opened position.

I claim:

The ornamental design for a towel cabinet or similar article, as shown.

MARTHA MAY HAGEDORN.
